(57) **CLAIM**

The ornamental design for a ring with fluted side, as shown and described.

DESCRIPTION

FIG. 1 is a perspective view of a ring fluted side showing my new design;

FIG. 2 a front view thereof;

FIG. 3 is a side view thereof;

FIG. 4 is a perspective view of a second embodiment of the ring with fluted side;

FIG. 5 a front view thereof;

FIG. 6 is a side view thereof;

FIG. 7 is another side view thereof;

FIG. 8 is a perspective view of a second embodiment of the ring with fluted side;

FIG. 9 a front view thereof;

FIG. 10 is a side view thereof;

FIG. 11 is a perspective view of a second embodiment of the ring with fluted side;

FIG. 12 a front view thereof;

FIG. 13 is a side view thereof; and,

FIG. 14 is another side view thereof.

The portions shown in broken lines illustrate portions of the ring with fluted side that form no part of the claimed design.

1 Claim, 14 Drawing Sheets
